UNITED STATES PATENT OFFICE.

PAUL MACGAHAN, OF PITTSBURGH, PENNSYLVANIA, ASSIGNEE TO WESTINGHOUSE ELECTRIC & MANUFACTURING COMPANY, A CORPORATION OF PENNSYLVANIA.

CIRCUIT CONNECTION FOR ELECTRICAL APPARATUS.

1,120,829.

Specification of Letters Patent. Patented Dec. 15, 1914.

Application filed October 18, 1905. Serial No. 283,840.

To all whom it may concern:

Be it known that I, PAUL MACGAHAN, a citizen of the United States, and a resident of Pittsburgh, in the county of Allegheny and State of Pennsylvania, have invented a new and useful Improvement in Circuit Connections for Electrical Apparatus, of which the following is a specification.

My invention relates to electrical apparatus and particularly to circuit connections therefor.

The object of my invention is to provide a simple, inexpensive and durable means for making electrical connection between the winding or windings of electrical apparatus and an external circuit and one which shall effectively exclude moisture, dust and other foreign matter from the casing in which the coils to which connection is made are located.

Figure 1 of the accompanying drawing is a view, mainly in section, of a portion of an electrical measuring instrument, and Fig. 2 is a view, in side elevation, of the terminal block, with the leading-in conductor in my section, my invention having been developed for application to electrical measuring instruments and having been practically applied thereto but without intention of necessarily limiting it to such specific use.

The casing 1 is shown as provided with an outlet portion 2 and as containing a laminated, magnetizable core 3 which is surrounded by a coil 4 to which connection is made from an external circuit. In order to make such connection and also to protect the coil and other devices which may be included within the casing, I provide the parts which will be now described.

Fitted to the free end of a terminal wire 5, leading from the coil 4, is a tube 6, of copper or other good conducting material and at a suitable point intermediate its ends, the tube is flattened as indicated at 7 in order that it may be accommodated to the space which it is designed to occupy and also in order that it may be readily bent without injurious effect. The portion of the tube 6 beyond the bend 7 fits closely within a hollow terminal block 8 of suitable insulating material and its outer end is threaded to screw into the inner end of a metal tube or terminal sleeve 9 having a suitable internal thread. The tube or sleeve 9 is seated in a corresponding recess or cavity in the outer end of the terminal block

8. The terminal block 8 makes a sufficiently close fit within the portion 2 of the casing to insure its retention therein, and it has a shoulder 10 that fits closely against the outer end of the portion 2. The inner end of the terminal block is provided with a recess or well 11 constituting an enlargement of the hole or passage containing the conductor 6 from which projects a recess or notch 11^a to receive the flattened portion 7 of the tube 6. The recess or well 11 may be filled with a body 11^b of suitable material, as indicated in the drawing. A binding device 12 is provided with a threaded portion 13 that screws into the tube 9 and thus serves to suitably bind a wire that may be coiled about it between the outer end of the tube and the outer portion of the device 12.

It will be understood from the illustration and the foregoing description that the device is of simple and compact construction and that it may be utilized to readily effect circuit connection between the winding 4 and the external circuit and at the same time close the opening in the projection 2 to prevent the entrance of any foreign matter which might be injurious to the internal mechanism.

I claim as my invention:

1. An electrical connector comprising an insulating terminal block having a conducting tube seated in its outer end, a tubular leading-in conductor having an angularly bent flattened portion at the inner end of the block and having its outer end seated in the inner end of the conducting tube.

2. An electrical connector comprising an insulating terminal block provided with a binding post at its outer end and having a tubular leading-in conductor that projects through it into engagement with the binding post and is flattened and angularly bent adjacent to the inner end of the block.

3. A terminal block, and a tubular leading-in conductor that projects into the block and has a flattened portion adjacent to the inner end of the block that is bent at an angle to the axis of the block.

4. An insulating terminal block having a notch in one end, and a tubular leading-in conductor that projects into said block and has a flattened portion that is bent at substantially a right angle to the axis of the block and rests in the notch.

5. The combination with a casing having

a tubular outlet portion, of a tubular insulating body seated in said outlet portion and having a lateral notch or recess in its inner end, and a stationary leading-in conductor having a portion axially disposed within said insulating body and a portion projecting laterally through said notch or recess.

In testimony whereof, I have hereunto subscribed my name this 13th day of October, 1905.

PAUL MacGAHAN.
